DESIGN FOR A PEN DESK STAND

Ray R. Hutcheson, New York, N. Y., assignor to Diecasters, Inc., New York, N. Y., a corporation of New York

Application July 18, 1936, Serial No. 63,923

Term of patent 3½ years

To all whom it may concern:

Be it known that I, Ray R. Hutcheson, a citizen of the United States, residing in Queens, in the city, county, and State of New York have invented a new, original, and ornamental Design for Pen Desk Stands, of which the following is a specification, reference being had to the accompanying drawing, forming a part thereof in which:—

Fig. 1 is a plan view of my pen desk stand according to the invention.

Fig. 2 is a side elevational view thereof and
Fig. 3 is a front view of Fig. 2.

I claim:

The ornamental design for a pen desk stand, substantially as shown.

RAY R. HUTCHESON.
